(57) **CLAIM**

The ornamental design for a game console button set, as shown and described.

DESCRIPTION

FIG. 1 is a front, right and top perspective view of a game console button set, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of the game console button set.

FIG. 10 is a rear, left and bottom perspective view of the second embodiment of the game console button set of FIG. 9.

FIG. 11 is a front elevation view of the second embodiment of the game console button set of FIG. 9.

FIG. 12 is a rear elevation view of the second embodiment of the game console button set of FIG. 9.

FIG. 13 is a left side elevation view of the second embodiment of the game console button set of FIG. 9.

FIG. 14 is a right side elevation view of the second embodiment of the game console button set of FIG. 9.

FIG. 15 is a top plan elevation view of the second embodiment of the game console button set of FIG. 9.

FIG. 16 is a bottom plan elevation view of the second embodiment of the game console button set of FIG. 9.

FIG. 17 is a front, right and top perspective view of a third embodiment of the game console button set.

FIG. 18 is a rear, left and bottom perspective view of the third embodiment of the game console button set of FIG. 17.

FIG. 19 is a front elevation view of the third embodiment of the game console button set of FIG. 17.

FIG. 20 is a rear elevation view of the third embodiment of the game console button set of FIG. 17.

FIG. 21 is a left side elevation view of the third embodiment of the game console button set of FIG. 17.

FIG. 22 is a right side elevation view of the third embodiment of the game console button set of FIG. 17.

FIG. 23 is a top plan elevation view of the third embodiment of the game console button set of FIG. 17.

FIG. 24 is a bottom plan elevation view of the third embodiment of the game console button set of FIG. 17.

FIG. 25 is a front, right and top perspective view of a fourth embodiment of the game console button set.

(Continued)

FIG. 26 is a rear, left and bottom perspective view of the fourth embodiment of the game console button set of FIG. 25.

FIG. 27 is a front elevation view of the fourth embodiment of the game console button set of FIG. 25.

FIG. 28 is a rear elevation view of the fourth embodiment of the game console button set of FIG. 25.

FIG. 29 is a left side elevation view of the fourth embodiment of the game console button set of FIG. 25.

FIG. 30 is a right side elevation view of the fourth embodiment of the game console button set of FIG. 25.

FIG. 31 is a top plan elevation view of the fourth embodiment of the game console button set of FIG. 25.

FIG. 32 is a bottom plan elevation view of the fourth embodiment of the game console button set of FIG. 25.

FIG. 33 is a front, right and top perspective view of a fifth embodiment of the game console button set.

FIG. 34 is a rear, left and bottom perspective view of the fifth embodiment of the game console button set of FIG. 33.

FIG. 35 is a front elevation view of the fifth embodiment of the game console button set of FIG. 33.

FIG. 36 is a rear elevation view of the fifth embodiment of the game console button set of FIG. 33.

FIG. 37 is a left side elevation view of the fifth embodiment of the game console button set of FIG. 33.

FIG. 38 is a right side elevation view of the fifth embodiment of the game console button set of FIG. 33.

FIG. 39 is a top plan elevation view of the fifth embodiment of the game console button set of FIG. 33.

FIG. 40 is a bottom plan elevation view of the fifth embodiment of the game console button set of FIG. 33.

FIG. 41 is a front, right and top perspective view of a sixth embodiment of the game console button set.

FIG. 42 is a rear, left and bottom perspective view of the sixth embodiment of the game console button set of FIG. 41.

FIG. 43 is a front elevation view of the sixth embodiment of the game console button set of FIG. 41.

FIG. 44 is a rear elevation view of the sixth embodiment of the game console button set of FIG. 41.

FIG. 45 is a left side elevation view of the sixth embodiment of the game console button set of FIG. 41.

FIG. 46 is a right side elevation view of the sixth embodiment of the game console button set of FIG. 41.

FIG. 47 is a top plan elevation view of the sixth embodiment of the game console button set of FIG. 41.

FIG. 48 is a bottom plan elevation view of the sixth embodiment of the game console button set of FIG. 41; and, FIG. 49 is another perspective view of the game console button set in a usable state.

The broken lines depict portions of the game console button set that form no part of the claimed design.
